UNITED STATES PATENT OFFICE

2,563,149

CARBON SHEET SUPPORTING DEVICE

Walter A. Anderson, Bridgeport, Conn., assignor to Underwood Corporation, New York, N. Y., a corporation of Delaware

Original application June 27, 1946, Serial No. 679,722, now Patent No. 2,536,524, dated January 2, 1951. Divided and this application June 16, 1948, Serial No. 33,305

8 Claims. (Cl. 197—126)

1

This invention is a division of application No. 679,722, filed June 27, 1946, now Patent No. 2,536,524, dated January 2, 1951, and relates to carbon-sheet anchorage provision in business machines, particularly also to such provision in association with facilities for front-feeding work-sheets into printing position in front of a platen.

Preparation of certain business papers or records calls in many instances for front-insertion of a work-sheet in a position behind a foremost, front-inserted sheet, for receiving business entries, such entries being usually limited to one line. The work-sheet behind the foremost work-sheet must receive its imprints through a transfer or carbon-sheet in front thereof.

To reduce the handling of such carbon-sheet to a minimum during the preparation of a succession of records or bills, it is of advantage to support or retain it on the machine, if provision is also made which will facilitate conveniently front-feeding of the necessary work-sheets.

It is therefore an object of the present invention to provide for carbon-sheet support in advantageous cooperative association with efficient facilities for front-feeding a work-sheet in front and a work-sheet in back of the supported carbon.

It is a further object to provide an efficient carbon-sheet supporting or anchoring device which is movable from a retired, carbon-sheet tightening, to a carbon-sheet slackening position, for facilitating substantially resistanceless front-feeding of a work-sheet behind the supported carbon-sheet and without carbon-smudging, in combination with an advantageously mounted front-feed table having a path of movement between a retired and a front-feed position which is different and independent of said device.

It is also an object to produce an efficient anchorage device for the leading end of a carbon-sheet, such device being capable of carbon-sheet slackening movement automatically in coordination with the conditioning movement of front-feeding facilities for a work-sheet to be front-fed in front of the anchored carbon.

In association with the foregoing objects, it is a further object to provide for movement of a carbon-sheet anchorage device from a normal to a displaced position, not only for the purpose of slackening the carbon-sheet, but also to make possible a more favorable angle for front-feeding a work-sheet therebehind, wherefore a work-sheet so front-fed requires also less flexing around the platen.

2

Another object is to provide an efficient anchorage device for the leading end of a carbon-sheet.

A still further object is to provide a carbon-sheet anchorage device of simple structure which is readily and conveniently applicable and removable from the machine.

In addition to the above specifically noted objects, there are other objects which in part are obvious and in part are pointed out as the description of the preferred embodiment of the invention proceeds.

Referring now to the drawings:

Figure 1 is a fragmentary right-hand side elevation of a Sundstrand Accounting Machine carriage, embodying the front-feed facilities disclosed in said application No. 679,722, all parts being shown in their normal positions.

Figure 2 is an enlarged sectional view of a carbon-sheet anchorage bar and an associated clip.

Figure 3 is a sectional side elevation of the carriage shown in Figure 1, showing also a fragmentary representation of a carbon-sheet anchorage device, all parts being in their normal relations.

Figure 4 shows in frontal aspect a portion of the carbon-sheet anchorage bar seen in Figure 2.

Figure 5 is a right-hand fragmentary sectional side elevation, illustrating the front-feed device in closed, sheet-holding position, together with the carbon-sheet supporting feature of the invention.

Figure 6 is a front perspective illustration of the carbon-sheet anchorage fixture or attachment, and finally,

Figure 7 is a view similar to Figure 5, but showing the front-feed device and carbon-sheet anchorage device in sheet-receiving position.

Only so much of said front-feed facilities are shown and described herein as are thought necessary in the presently featured invention. However, reference may be had to said prior application, if such is necessary for an understanding of the invention.

Referring now particularly to Figures 1 and 3, the machine comprises a paper-supporting carriage 2, comprising two spaced side-walls 111 between which a platen 7 is turnably accommodated for paper-feeding control, in a conventional manner. The side-walls 111 of the carriage are rigidly interconnected by means including rail bars 113, 114, between which there is a track structure 116, constituting part of the main frame-work of the machine and cooperat-

ing through the medium of anti-friction elements 118 with the rail bars 113, 114 to provide guidance for the carriage. The parts 113, 114 and 116 are all disposed to accommodate low-slung guiding means for efficient front-feeding of work-sheets, as will become evident later. Both end-plates 111 of the carriage have flanged side covers indicated at 111^a in Figure 1.

Usually accounting machines are required to hold a minimum of one journal or record sheet, and a minimum of one ledger or statement sheet. In Figure 3 a record sheet is designated by the reference character R, and a statement sheet by the reference character S. The record sheet R, see Figure 3, is rear-fed and receives a carbon record of entries made upon successively front-fed statement sheets, there being a carbon-sheet, not shown, inserted therewith. The statement sheet S is front-fed because it requires very frequent handling, whereas the record sheets do not.

Record sheet holding and feeding devices

Feed-rolls 134 bear normally resiliently upon the rear-side of the platen 7, below the level of a platen shaft 112, and other feed-rolls 135 bear normally upon the top-side of the platen, all to hold a record sheet R in typing position on the platen. Above the feed-rolls 134, extending between the carriage ends 111, and inclined rearwardly, there is a sheet-supporting table 136 rigidly fastened to the carriage ends 111. The record sheet R is fed downwardly in front of said table 136, and rolled between said feed-rolls 134 and the platen, forwardly and upwardly, by turning the platen 7.

The top feed-rolls 135 are parts of feed-roll units 140 that are adjustably movable along a bar 141 which is pivotally supported in the carriage ends to allow the rolls to be cast off, by means not shown. An apron 154 attached to the bar 141 covers the several feed-rolls 135 and their supporting units. It serves to guide and keep front-fed work-sheets from contacting the feed-rolls 135 and their supporting structures.

The bottom feed-rolls 134, of which there are a series alongside of each other, are supported on levers 156 pivoted upon a common pivot rod 157 that is carried by a web 158 on the carriage. A cam shaft 161 is provided for cooperation with the levers 156 to cast the feed-rolls 134 a small distance from the platen. The means for turning the shaft is not shown. The feed-roll supporting-levers 156 have tapered tongues 163 reaching forwardly from the feed-rolls 134 in slightly spaced relationship to the platen, such tongues being instrumental to guide rear-fed sheets, such as the record sheets R, in a curved path around the underside of the platen.

Front-feed table and throat

Figures 3 and 5 show a statement sheet S in position for receiving imprints from types 10. Paper-holding means in the form of feed-rolls 168 bear against the front-bottom side of the platen 7 to hold said statement sheet and also to assist in holding and feeding other sheets on the platen. Above the typing line, which is directly at the front side of the platen, a front-feed guide or table 170, preferably of transparent material, bears rearwardly against the statement sheet S. With the front-feed table 170 in the position described, the type-bars 10 can rise freely for making the appropriate typing impressions. Usually after a single line-entry the statement sheet S is removed and another is

presented, the record sheet R remaining in the machine and being line-spaced in a usual manner by a turning movement of the platen.

As illustrated in Figure 7, in order to facilitate removal of one statement sheet S, and the introduction of another in its place, the paper-holding means or feed-rolls 168 are cast off the platen 7 to provide a wide-open front-feed throat, and the front-feed table 170 is displaced to a forwardly tilted position.

The transparent front-feed table 170 may be co-extensive in length with the platen, and is secured along its upper margin to a stiff bar 171. The bar 171 is carried at the opposite ends of the carriage by plates 173 which are pivoted to the adjacent side-walls 111 of the carriage by means of pivot studs 174 which are located on an axis that lies parallel, to the rear and below the platen axis. Said pivot studs 174 render the front-feed table movable between a normal, re-tired position in back of the types 10, see Figures 1, 3 and 5, to a front-feed position seen in Figure 7.

Said feed-rolls 168 extend in a row along the platen and each is rotatively supported by two spaced arms 175 carried swingably upon a supporting shaft 176. Brackets 178 afford bearing supports for the shaft 176 and springs 177 associated with the arms 175 urge the latter, and thus the feed-rolls 168, constantly towards the platen. The feed-rolls 168 are released by a rocking motion given the shaft 176 whenever the carriage is conditioned for front-feeding, in a manner to be stated later.

The sheet S which is front-fed down between the platen and the feed-rolls 168, see Figure 7, take a wide sweep rearwardly below the tapered tongues 163 extending forwardly from the rear feed-rolls 134. Such wide sweep is given the sheets by guiding elements 185, see Figures 5 and 7, situated between the feed-rolls 168, and below which the latter withdraw when released. The said guiding elements 185 are augmented in their function by a paper shelf 186, which has a slight upward tilt to the rear. Spaced deflector elements 192, embodying narrow sheet-deflecting shelves 192^a at circumferentially reduced intermediate parts of the individual feed-rolls 168, are nested closely to the platen when said feed-rolls 168 are in applied position, but move an appreciable distance from the platen when the feed-rolls are cast off, that is when the carriage is conditioned for front-feeding work-sheets as seen in Figure 7. During the release of said feed-rolls 168 the deflector elements 192 will all be moved downwardly by the engagement of the lower part of the reduced feed-roll sections therewith, but downward movement commences only after the feed-rolls have withdrawn below the deflector shelves 192^a.

Thus it will be seen that a work-sheet S is introduceable with ease into the open front-feed throat. See Figure 7.

Manual front-feed conditioning

The front-feed table 170 and the feed-rolls 168, see Figure 1, are movable to front-feed position by an operating handle 195, carried on a composite slide structure generally designated by the numeral 196, and consisting of a flat stamped-out slide 197 having a stiffening angle member 198 riveted to the former as indicated at 200. The composite slide 196 is carried upon the right side-wall 111 of the carriage, slightly spaced therefrom, by means of headed screw-studs 201

extending through slots 202 in the slide 197. Accommodated between the slide 197 and the carriage side-wall 111 is a link member 203 which at its forward end has a pivotal connection with a stud 205 projecting from the right end-plate 173 of the front-feed table 170, said stud 205 reaching through a clearance aperture in the right carriage end 111, and in conjunction with said aperture affording limits for opposite movement of the front-feed table. The link 203, near its rear, has guidance parallel to the slide 196. In the rearward position of the front-feed table, see Figure 1, an operating pin 209 projecting from the slide 197 is directly behind the rear end of the link 203. Therefore, when the operating handle 195 is imparted a forward movement, said link 203 will be displaced forwardly to swing the front-feed table 170 to the front-feed position seen in Figure 7.

In order to release the feed-rolls 168 from the platen at the same time that the front-feed table 170 is displaced forwardly, the aforesaid feed-roll releasing shaft 176 has affixed thereto, see Figure 1, an upright arm 211 having a forked end embracing a projecting pin 213 on the slide 197. The composite slide 196 is normally resiliently retained in its rearward position by means of a spring 214 anchored to the adjacent carriage wall 111. In turn the link 203, and therefore also the connected front-feed table 170 are resiliently urged rearwardly by a spring 215 arranged intermediate the slide 197 and the link 203. To retain the front-feed facilities in front-feed condition after movement thereto, there is provided a latch arm 216, pivotally supported upon the carriage as at 217, and having a laterally bent lug 218 thereon to catch behind a shoulder 219 on the slide 197 as such slide approaches its forward limit position. The front-feed device is restorable to normal condition under control of a key 221 pivoted as at 223 on the carriage, and having a rearwardly extending arm 224 underlying a lateral tab 225 on the latch arm 216.

The machine embodies also means to open and close the front-feed mechanism under carriage control, but the means for this is not shown.

Carbon ply and anchorage fixture therefor

It has been said that some billing or accounting work calls for front insertion of a work-sheet behind the foremost sheet, namely behind the statement sheet S. Such a work-sheet is given the designation S' in Figures 5 and 7. Impressions on this sheet S', for a minimum of handling, are preferably made through the medium of a continuous transfer or carbon-ply 379, as supplied from a roll 378 located at the rear of the platen, the ply extending from the roll to the front of said sheet S'. Accordingly, see Figure 3, there are mounted adjustably along a rod 375 on the carriage opposite carbon roll supporting brackets 376 having pintles 377 reaching toward each other for supporting a carbon roll 378. From said roll the carbon paper or ply 379 is passed forwardly and downwardly from the roll, underneath the bottom feed-rolls 134, and upwardly behind the front-feed table 170 over the top feed-rolls 135 for anchorage of a leading end of the carbon-ply on an anchorage device or fixture generally designated by the numeral 391. The fixture 391 consists of a removable unit, shown in Figure 6, comprising two widely spaced end-plates 392 connected by a bar 393 having ends 394 rectangularly bent therefrom and rigidly united with the end plates 392 by screws 395.

and 396. A plate 397 is secured to the back of the bar 393, as by rivets, not shown, and rises thereabove a short distance to afford a clamping surface for engagement by a carbon-ply clamping rod 398 that is substantially co-extensive with the bar 393. This rod 398 is supported at each of its opposite ends on a member 400, each of which, as at 399, is pivotally carried on the adjacent end-plate 392, the rod and the members forming a unitary, pivoted bail structure, and a contractile spring 401 associated with each opposite member 400 being adapted to urge the rod 398 into clamping association in a corner formed by the top surface of the bar 393 and the front of the plate 397, the leading end of the carbon-ply having previously been positioned between the rod 398 and the plate 397.

In certain business applications it is impractical and sometimes unnecessary to use the carbon-holding fixtures. For that reason such fixture is constructed as a removable unit. See Figure 6. Moreover, for reasons to be pointed out, it is desirable that the fixture 391 swing forwardly incidental with the forward displacement of the front-feed table 170, but in a path and to a degree different from that of the latter. Accordingly the end-plates 392 are formed with open saddles 403 to fit over pivot pins 404 projecting inwardly from the opposite side-walls 111 of the carriage. Additionally said end-plates 392 are each formed with an open slot 405 for operative association with pins 406 extending inwardly from the opposite plates 173 which support the front-feed table 170. The slots 405 are at the bottom open-mouthed as at 405a, so that the fixture can be dropped readily into position on the carriage, the plate portions forming the saddles 403 at the opposite ends of the carriage being directed downwardly just in front of the usual mounting collars 407 of the platen. See Figures 5 and 7. Detent levers 408, shaped at the bottom to reach at least partially underneath the pivot pins 404, and urged by the springs 401 to so reach underneath, serve to hold the entire fixture 391 removably assembled on the carriage. The end-plates 392 and the detent levers 408 have tapered entrance faces facilitating placement of the fixture upon the pivot pins, the detent levers 408 during such placement being momentarily yielding. The fixture can be removed readily and conveniently by exerting upward pressure thereon and thereby forcing said detent levers 408 from under the pivots 404. Pivotal support for the detent levers 408 is afforded by the screws 396, which for this purpose are shouldered. The saddles 403 with the associated detent levers 408, and in conjunction with the pivot pins 404, constitute resilient clasping means for readily and removably associating the carbon sheet anchorage device with the machine.

When the front-feeding device is in normal position, that is in writing position, as seen in Figure 5, the carbon-ply may be in a condition stretched tightly around the bottom and front-side of the platen. When the front-feed device is moved to open position as seen in Figure 7, the carbon anchorage fixture 391, through the pins 406, is also moved forwardly, and slightly slackens the carbon-ply 379 to bulge from the platen, thereby to relieve pressure from the underlying work-sheet S', and to prevent smudging of such sheets when they are removed, inserted, or readjusted. The carbon-ply is slackened by reason of the particular path through which the fixture 75 swings during the opening movement of the

front-feed device. Such slackening is very little but yet effective. Obviously, similar to the table 170, the plate 397 constitutes a front-feed table.

It will be noted that the pivotal axis for the table 170, as afforded by the pins 174, is chosen to give the table a movement downwardly and forwardly from retired to front-feed position. This brings the table to an advantageous, low front-feed position. During front-feed table retiring, the lower edge of the table moves upwardly and rearwardly to smoothen the inserted sheet S tightly against the platen. On the other hand, the pivotal axis for the carbon-sheet anchorage device 391 is so located that the anchorage bar 393 has an appropriate carbon-sheet slackening action as the machine is conditioned for front-feed.

It is to be understood that the slackening of the carbon-ply 379 provides clearance for front insertion of the sheet S', and, obviously the forward tilting of the carbon anchorage fixture gives also a more favorable angle of introduction for the sheet S', while it also reduces the necessary bend which the sheet must receive during insertion. The top edge of the plate 397 may serve as a gaging edge for the top edge of the sheet, but bottom edge gaging means, not shown, may be employed if this is found desirable.

The spring 401, which serves the dual purpose of pressing the rod 398 into clamping contact upon the carbon-ply 379 and urging the lever 408 into fixture-holding position, exerts its force below the pivot stud 399 when the rod 398 is in carbon-holding position. The clamping rod 398 can be thrown off the plate 397 as indicated in dot-and-dash lines in Figure 7, by pushing finger tabs or flanges 410 of the members 400 rearwardly. In so doing a pin 411 on each member 400 rides over a hump on the upper end of the adjacent lever 408, and is finally caught in a detent notch 413 under the tension of the spring 401. To apply the rod, forward pressure is applied to the tabs 410, forcing the pin 411 out of detent notch 413 and over the said hump.

The clamp comprising the rod 398 and the plate 397 is released at intervals to draw the carbon-ply a short distance upwardly and thereby to secure an unused transfer field for use, the extending portion of carbon-ply being torn off against the serrated top-edge of the plate 397.

Usually carriages are of necessity of considerable length, and the rod 398 being relatively thin is preferably arched to the rear slightly for better intermediate clamping contact. To improve the clamping contact of the rod further, spring clips, generally designated by the numeral 414, see especially Figures 2, 4 and 6, are applicable to the fixture 391. The clips are formed of flexible sheet material and comprise a main body portion or web 415, from which there are bent to double over the web, a main spring prong 416 and two flanking spring prongs 417. The clips are applied to the fixture downwardly over the rod 398 and the plate 397, the lower end of the prong 416 finally bearing resiliently against a beveled bottom edge of the bar 393, and the lower ends of the prongs 417 being forwardly bent to exert rearward and downward pressure on the rod 398. So many of the clips 414 are attached as may be required to firmly anchor the carbon web 379.

The front-fed sheet S is positionable in correct lateral relation to other work-sheets by a left and/or right side edge gage 421, secured to the square bar 171. For locating the work-sheet S', which is front-fed down behind the carbon an-

chorage device 391, one or two of the clips 414 may be provided with side edge guides 418 which are bent rearwardly from the main web 415 of the clip 414.

5 The invention has been described with reference to the details shown in the drawings, but it is to be understood that variations in the construction and method of operation may be resorted to without departing from the spirit and scope of the invention.

10 What is claimed is:

15 1. In a business machine, the combination with a platen and a platen supporting framework, of a carbon-sheet anchorage attachment, clasping means oppositely on said attachment and said framework to hold said attachment removably on said framework, as well as swingably about an axis which extends parallel to the platen, means including a bar on said attachment to secure a carbon-sheet to the attachment along a line extending substantially parallel to said axis, and means to restrict the said attachment for swinging between one or another position.

20 2. In a business machine, the combination with a platen and a platen supporting framework, of a front-feed device comprising a front-feed table, means to mount said front-feed device for fore-and-aft displacement of said front-feed table, a carbon-sheet anchorage attachment, clasping means to hold said attachment removably on said framework, as well as swingably fore-and-aft about an axis which extends parallel to the platen, means for anchoring a carbon-sheet to said attachment along a line extending substantially parallel to said axis, and means on said attachment and said front-feed device for automatically establishing an articulate connection therebetween as the attachment is placed in clasped position on said framework, whereby then a displacement of said front-feed device fore-and-aft results in a fore-and-aft swinging displacement of said attachment.

25 3. In a business machine having a platen, typing means adapted to type upon the front of the platen, a front-feed table mounted for movement from a rearward, retired position, in a path downwardly and forwardly to a position facilitating front-feeding of a work-sheet, carbon-sheet anchorage means behind the front-feed table and mounted for displacement from a normal typing position to a front-feed position, forwardly and upwardly in a path different from said front-feed table, to loosen slightly a carbon-sheet anchored to said anchorage means and hugging the platen around the front and bottom, and means to move said front-feed table and said anchorage means to their respective front-feed positions concomitantly in their said respective paths.

30 4. In a business machine having a rotatable platen, typing means adapted to type upon the front-side of the platen along a typing line, paper-holding means normally bearing against the platen below and to the rear of the typing line, a front-feed paper table normally disposed above said typing line in an out-of-way position of the typing means, means mounting said front-feed table for movement forth and back between said out-of-way position and a front-feed position in a manner so that a bottom edge of said table in the back-movement of the table will describe an appreciable upward and rearward sweep to wrap a front-fed work-sheet snugly around the platen, carbon-sheet anchorage means behind the front-feed table, means mounting the said anchorage means for movement between a typing

and a front-feed position, pivotally about an axis parallel to the platen and lying in the neighborhood of the typing line, and means to move said front-feed table from said out-of-way position to said front-feed position and concomitantly to move said anchorage means from said typing position to said front-feed position.

5. In a business machine having a platen; supporting means for the platen at the ends thereof, a front-feed table, means including movable side members to mount said table on said platen supporting means for forward movement from a writing to a front-feed position, a carbon-sheet anchorage device comprising an elongate bar and end brackets rigid therewith, and means for readily and removably applying said anchorage device to said platen supporting means, and in a condition of operative association with said side members, said applying means comprising, pivot pins and open pivot seats oppositely on said end brackets and said platen supporting means, and a pin and a slot oppositely on at least one of said end brackets and one of said side members for providing an operative connection between said table and said anchorage device.

6. In a business machine having an elongate platen, a carbon anchorage device comprising, an elongate bar, a long, frail clamping rod mounted for swinging movement towards and away from said bar respectively to engage and release a carbon sheet, and a plurality of spring clips removably applied to said bar and rod at different locations therealong, to press the bar and rod resiliently together at the said locations for firm gripping of the carbon sheet.

7. In a business machine having a platen, means adapted to effect imprints along the front of said platen, a front-feed table mounted for

movement from a rearward, retired position in a path forwardly and downwardly to a position facilitating convenient front-feeding of a work-sheet, another front-feed table behind said first one, means to anchor to this other table a carbon-sheet supplied around the bottom of the platen, means to support said other table for movement from a retired position forwardly to a front-feed position, in a path independent from the first said table, and single means for moving both said tables from their retired to their front-feed positions.

8. In a business machine, an openable and closeable front-feed throat, two front-feed tables, one to the rear of the other, and both normally in retired rearward positions, means to anchor to the rear table a carbon-sheet supplied through said front-feed throat upwardly from the rear, means to support said tables for movement in different paths forwardly from their retired positions to positions for front-feeding work-sheets into said throat, and means for opening said front-feed throat and moving both said tables to their front-feed positions in a single operation.
